TRACTION BELT

Donald Stuart Kennedy, Longparish,
EnglandApplication November 3, 1932, Serial No. 641,067,
and in Great Britain November 9, 1931

8 Claims. (Cl. 305—10)

This invention relates to the construction of shoes for traction belts for road vehicle wheels and of the overall type. A traction belt of the overall type is described in my prior Patent Specification No. 1,808,416.

The present invention has for its principal objects to give improved track-adhesion, to prevent wheel spin inside the shoe, to render the shoe to some extent self-cleaning and to facilitate storage and also operative fixing of the chain.

My improved shoe comprises a main tread portion having lateral flaps or wings hinged or pivoted thereto, means being provided for limiting the outward-opening or outward extending movement of the flaps or wings, away from the normal trough-forming position, but so that the wing in said outward movement cannot exceed a position in which the plane of the wing is substantially in alinement with the plane of the main tread or is about parallel therewith. Each side of the main tread portion of the shoe may be provided with bosses or projections acting as stops to limit the outward movement or outward swing of the wing.

The main tread portion of the shoe preferably consists of a plurality of channel-section members arranged transversely of the shoe and having oblique or offset ends or spurs to their walls so as to embrace to a small extent the tread of the wheel tire. These channel-section members are spaced apart by means, for example, of washers or the like distance pieces through which the fore and aft extending bolts or spindles are passed, these retaining bolts passing also across the ends of the walls of the channel-section members and forming pivotal connections for the side wings or flaps. The side wings are provided with folds or loops which pass into the channel of the channel-section members and are there traversed by the said retaining bolts.

Instead of spacing washers between the channel-section members, the lateral flaps or wings may be provided with additional folds or loops which separate and space apart the channel-section members.

The present invention is hereinafter described with reference to the accompanying drawings, in which:—

Fig. 1 is an edge view of the improved shoe in its opened out position, one side flap or wing being shown detached.

Fig. 2 shows a half plan view of the tire-engaging side, and Fig. 2a the half plan of the underside of the shoe. Fig. 3 is an end elevation showing the side flaps in their inwardly closed

position. Fig. 4 is a side view of Fig. 3 taken on line 4—4 thereof. Fig. 5 is a plan of one of the side flaps detached. Fig. 6 is a plan view showing a separate spacing washer as the distance piece.

Fig. 7 is an elevation, part section, of a spring-loaded link member, and Fig. 8 is a plan thereof. Figs. 9 and 10 relate to a modification of Figs. 7 and 8.

Fig. 11 is a detail view of the offset end of one of the channel section members.

Fig. 12 shows a modification of the side flap mounted upon a shoe composed of three channel-section members.

The main tread portion of the shoe is shown composed of a plurality of parallel and channel-section metal members *a a*¹ set transversely of the line of travel of the traction belt, these members *a a*¹ being separated by distance pieces *c* or *d* hereafter described. A space or gap *a*² is thus left between the parallel members *a* and *a*¹.

The edges *b* of the walls of the channels of these members *a a*¹ are arranged to be engaged by the tread of the wheel tire (not shown). These members *a a*¹ have oblique or offset ends or spurs *b*¹, these spurs embracing to some slight extent the tire tread. These offset ends are shown provided with outer faces *b*² and *b*³.

In Fig. 2, the channel-section members *a a*¹ are spaced apart by the loops *d*⁶ hereafter described, while in Fig. 6, the channel-section members *a a*¹ are shown spaced apart by separate washers *c* forming the distance pieces. The preferred shape of the channel-section members *a a*¹ will be clearly seen in Fig. 4.

The side flaps or wings *d d* are of metal and provided with folds or loops *d*¹ *d*² which engage suitable pins or spindles such as the bolts *e e* extending fore and aft of the shoe so that the side flaps or wings *d* are hinged upon such bolts *e e*. These bolts *e e* also pass through the channel-section members *a a*¹ and the spacing washers *c* or other distance pieces, and they are shown provided with retaining nuts *e*¹.

The offset ends or spurs *b*¹ are deeper or higher than the walls of the members *a a*¹ in the flat portion of the main tread of the shoe. They also extend laterally well beyond the bore for the retaining pins or bolts *e e*, and their outer surfaces are provided with contact faces *b*² *b*³. These faces *b*² *b*³ are above the level of the tread-engaging edges *b* and are angularly shaped and inclined one to the other (see Fig. 11).

The side wings *d d* are corrugated or grooved as shown at *d*³ from about their outer extremity up

to the end adjacent to the retaining pin or bolt e , i. e. in a direction transverse of the shoe. The concave face of the corrugation or groove is towards the ground and the convex face is towards the side wall of the tire. The inner end of the wall of this groove or corrugation d^3 is in prolongation of the space between two adjacent channel-section members a a^1 . A portion of the shoe d , is cut away to form a shoulder portion d^4 , which shoulder is arranged to abut against the contact face b^2 as shown in Fig. 3, so that the inward movement of the side wing d is limited. These cut-away portions forming the shoulders d^4 are adjacent to the hinge-forming folds or loops d^1 d^2 in the wings. This inwardly-closing limitation is preferably such that the side wing d cannot take up a position in which its plane is at less than 110° to the plane of the main tread a a^1 . I do not limit myself to that angle but it is important that the angle between the wing d and the main tread a a^1 should always be considerably more than 90° .

On the other hand, limitation of the outward opening movement of each wing d is provided by the contact face b^3 with which the shoulder d^4 of the wing can make contact. This outward limitation is such that the maximum outward movement permitted is one in which the plane of the wing d is substantially in alignment with the plane of the main tread a a^1 of the shoe, or is about parallel therewith, as will be understood from Fig. 1.

Instead of introducing a separate spacing washer c to form the distance piece between the members a a^1 , (Fig. 6), I prefer to provide each side flap or wing with the third fold or loop d^3 , as shown in Figs. 2 and 5, to form the distance piece; this intermediate loop d^3 , also pivoted on the pin e , thus acts to hold apart the adjacent walls of the two members a a^1 .

It will be noted that the shoulder d^4 in the wing d can make contact with either the face b^3 or the face b^2 , so that in one direction it limits the outward-opening movement and in the other direction limits the inward-closing movement of the wing d .

The wings d may each be formed with slightly curved outer extremities as shown at d^7 . The fold or loop d^1 d^2 around the retaining bolt e e may be continued back and such continuation be secured to the metal plate of which the wing is formed: that construction will be clear from the detached portion of Fig. 1, the wing d , the loops d^1 d^2 and the continuation d^5 being integral. In such case, the shoulder d^4 is cut into both plate d and continuation d^5 .

Preferably, space is left between the folded back portion or continuation d^5 and the plate d to form a housing d^8 into which two ordinary chain links f can be inserted from opposite ends (see Fig. 2a), each such link f (at the end of the short length of chain connecting adjacent shoes) being retained between the folded back portion d^5 and the plate portion d of the side wing by a nutted bolt f^1 passing through a hole f^2 in the wing d and through a corresponding hole in the portion d^5 so that the end link f can pivot about the bolt f^1 . The folded back portion d^5 also extends from the leading edge to the trailing edge of the wing as can be seen in Fig. 2a, being integral with and supported by the three loops d^1 d^2 d^6 . When the middle loop d^6 is omitted, the distance piece being formed by a washer c (as in Fig. 6), the folded back portion d^5 is supported by the two loops d^1 d^2 .

Instead of ordinary oval chain links f between adjacent shoes, I may in some cases provide these hinged side wings d with resilient link members between two successive shoes. These resilient link members may comprise barrels g (see Figs. 7 and 8) fitted with enclosed springs h arranged intermediately of the length of the link and between the component parts thereof, in such a manner that the springs will automatically take up any slackness between adjacent shoes in the overall chain due to wear of the links f . This resilient link member is pivotally connected at each end to a shoe member, either directly or by means of a single coupling link i , or a twisted link i . One end of the barrel g is shown bored as at g^2 (see Fig. 7) for the sliding stem j^1 of the plunger j around which is mounted the coiled spring h , and the projecting end of the stem j^1 is secured to or otherwise connected with a loop g^3 pivotally connected with the adjacent shoe, as by means of a twisted link i . The resilient link member can be quickly inserted into position between adjacent shoes to replace worn or stretched chain links or other connections between those shoes.

The resilient link member may be made as a shackle comprising parallel side bars g^1 and rounded or other suitable ends g^4 , as indicated in Figures 9 and 10. One such end g^4 is shown looped through a twisted link i^1 which can be connected to a pivotal axis upon one shoe. The other end is bored to receive a sliding stem j^4 , similar to the stem j^1 shown in Fig. 7 and connected to a second twisted link i^2 . The head j^3 of this stem j^4 is notched on opposite sides as at j^2 (Fig. 10) to engage the inside faces of the parallel side bars g^1 of the shackle, so that the sliding movements of the stem or plunger are guided by the said bars and distortion of the spring h^1 is avoided.

The channel-section members a a^1 on their track-facing sides may be provided, if desired, with strakes of the known kind, riveted to the channel-section members, one such strake being shown at a^3 in Fig. 1 and in Fig. 2a, secured by rivets a^4 . While I have illustrated the tread portion of the shoe as composed of two channel-section members, spaced apart by washers or distance pieces, I may of course employ more than two such members, with distance pieces arranged between each adjacent pair. Fig. 12 shows by way of example three channel-section members a a^1 a^1 and two separate distance pieces c , the wing d^0 being provided with three loops d^9 to engage the hinge bolt e ; these three loops are continued to form a back portion housing the chain link connections, as described with reference to Figs. 2 and 2a.

When the traction belt made up of these shoes is in normal conditions fitted to the two rear wheels of a six-wheeled road vehicle, the shoes assume the form of a trough due to the linkages f between adjacent shoes pulling the wings d inwardly against the walls of the wheel tires on the tandem rear wheels on one side of the vehicle. The wings d can, however, move outwardly (until the limit is reached) under conditions of stress and in so doing increase the area of contact with the ground and add to the width of the tracked area for the tires of those tandem wheels to roll upon.

Nevertheless, by limiting their outward movement, the wings are prevented from being accidentally pulled under the shoe during service,

or when the chain is being affixed in operative position upon the wheels.

For storage purposes, the wings and main tread portion of the shoe open out approximately flat (Fig. 1). The hinged connection of the wings *d* and the open gap *a*² between each two channel-section members *a* *a*¹ will render the shoe to some extent self-cleaning. The rounded or domed corrugation *d*³ in the side wings prevents undue wear on the side walls of the tire, the transverse open gap *a*² in the tread portion improves road-adhesion, and the edges of the walls *b* of the channel-section members reduce wheel spin within a chain of these shoes.

15 The pivoted wings or flaps *d*, which are normally turned inwards to form the sides of the trough in which the wheel tires travel, have their outward movement limited so that they cannot exceed the alined or parallel position

20 when the trough becomes flattened out, for example, under conditions of stress or when the overall chains are detached for storage, and the hinge or pivotal movement of the flaps *d* is in all cases restricted by limiting stops provided

25 between the pivoted wings and the main tread portion.

What I claim is:—

1. A shoe for a traction belt comprising a main tread portion, consisting of a plurality of channel-section members laid transversely of the shoe, offset ends to said channel-section members adapted to embrace to some small extent the tread of a wheel tire, and side wings pivotally connected with the ends of said channel-section members, said offset ends being provided also with contact faces forming stops to limit the outward movement of the said wings.

2. A traction belt shoe, comprising a tread portion set across the line of travel of the belt, said tread portion including a plurality of parallel channel-section members, side wings hingedly connected by pins to the ends of said tread portion, and distance pieces provided between the said channel-section members, said distance pieces being traversed by the said pins.

3. A traction belt shoe, comprising a tread portion set across the line of travel of the traction belt, said tread portion including a plurality of parallel channel-section members, lateral wings hingedly connected by pins to the sides of said tread portion, and distance pieces engaging the walls of said channel-section members, said distance pieces being provided partly in the form of loops integral with said lateral wings and partly in the form of separate washers, all said distance pieces being traversed by said pins.

4. A shoe for a traction belt of the type described, comprising a tread portion set across the line of travel of the traction belt, said tread portion including a plurality of parallel but spaced apart channel-section members, side wings hingedly connected by hinge pins to the ends of said tread portion, and loops upon said side wings engaging the said hinge pins and entering respectively into the channels of the said channel-section members and into the space between adjacent channel-section members.

5. A shoe for a traction belt of the type described, having a main tread portion set across

the line of travel of the belt, a lateral wing pivotally connected to said tread portion on each side of the said line of travel, and upper and lower contact faces provided on the said tread portion to limit respectively the inward-closing movement and the outward-opening movement of the hinged wings, these contact faces being angularly inclined to each other.

6. A shoe for a traction belt of the overall type comprising a main tread member, side wings hinged thereto, coupling linkages with adjacent shoes, said linkages being secured to said side wings, and means for restricting in both directions the hinge movements between the said side wings and said tread member, said restricting means for each wing including a plurality of limiting stops provided upon the said tread member, and a stop provided upon the said wing, said stop co-operating with one of said limiting stops on the tread member to limit the said hinge movement in one direction and with another of said limiting stops on the tread member to limit the said hinge movement in the opposite direction.

7. A shoe for a traction belt of the overall type, comprising a main tread portion formed of a plurality of parallel channel-section members set transversely of the line of travel of the traction belt, side wings mounted upon the ends of said tread portion and pivotally attached thereto by pins which extend from the leading edge to the trailing edge of said shoe, a fold upon each said wing forming a distance piece between each two adjacent channel-section members, said pins traversing said channel-section members and said folds, coupling linkages secured upon the side wings of the shoe, offset ends to said channel-section members, contact faces upon the outer surface of each of said offset ends, the said contact faces upon each such end being inclined to one another, and a shoulder upon each side wing, said shoulder adapted to make contact during the movements of the pivoted wing with either of said inclined faces.

8. A shoe for a traction belt of the overall type, comprising a main tread portion formed of a plurality of parallel channel-section members set transversely of the line of travel of the belt, side wings mounted upon the ends of said tread portion and pivotally attached thereto by pins extending from the leading edge to the trailing edge of said shoe, coupling linkages secured to the side wings of the shoe, distance pieces engaging the walls of said channel-section members, said distance pieces being provided partly in the form of loops integral with said side wings and partly in the form of separate washers, said pins traversing said channel-section members and also said loops and said washers, offset ends to said channel-section members, contact faces upon the outer surface of each of said offset ends, the said contact faces upon each such end being inclined to one another, and a shoulder upon the side wing, said shoulder adapted to make contact during the movements of the pivoted wing with either of said inclined faces and to limit the respective swinging movements of said wing.

DONALD STUART KENNEDY.
